Inventor

UNITED STATES PATENT OFFICE.

MAXIMILLIAN A. MILLER, OF BALTIMORE, MARYLAND.

MUSICAL TOY.

Application filed February 14, 1922. Serial No. 536,402.

To all whom it may concern:

Be it known that I, MAXIMILLIAN A. MILLER, a citizen of the United States, residing at Baltimore, in the State of Maryland, have invented certain new and useful Improvements in Musical Toys, of which the following is a specification.

This invention relates to musical toys, and more specifically to a musical doll.

10 The main object of this invention is to provide a doll with means within its body for producing a harmonizing succession of sounds, so that the doll will simulate a person singing or humming, or of a person 15 playing an instrument when the doll is standing or sitting at a toy piano or the like. Another object of the invention is to provide within the body of the doll a mechanical operating mechanism for the musical 20 instrument, such operating mechanism being provided with a spring motor and with means for manually controlling the motor, this means being conveniently located for manipulation, and yet being in position to 25 be hidden by the clothing of the doll.

Other objects and advantages will be pointed out or implied in the following details of description in connection with the accompanying drawings in which:

30 Figure 1 is a sectional view of the musical device and its operating mechanism, the section being taken substantially along the line 1—1 of Figure 2;

Figure 2 is an edge elevation of the mechanism shown in Figure 1, the shutter being omitted.

Figure 3 is a rear elevation of a doll's body having the musical instrument and its driving and controlling mechanism attached 40 thereto.

Referring to these drawings in detail, in which similar reference characters correspond with similar parts throughout the several views, the invention consists in the combination of parts, as will now be described in the following:

The doll's body is indicated at 5, this body being hollow and provided with an opening 6 in its back. Within this opening is a 50 frame 7 of any suitable metal or material, this frame comprising two parallel plates 8 and 8' between which is located a train of gearing which includes gear wheels 9, 10, 11, 12, 13, 14 and 15, the latter being in 55 mesh with a worm 16 which is journaled in suitable bearings 17 and 18 of the frame 7.

A fan 19 is united with the worm 16 and constitutes a governor for regulating the speed of the train of gearing.

The gear wheel 11 is mounted on a shaft 20, and to this shaft is secured a motor-spring 21, the outer end of this spring being secured to the frame 7. The shaft 20 is provided with a non-cylindrical outer end 22 for engaging with a key for turning this 65 shaft and winding the spring 21. A ratchet is provided at 23 for connecting the wheel 11 with the shaft 20, so that the spring 21 drives the wheel 11 through the medium of the shaft 20. Because of the relation of 70 this wheel 11 to the previously mentioned gear wheels 12 to 15 inclusive, the worm 16, and fan 19, it rotates at a relatively slow speed, and in thus rotating it causes the gear wheels 10 and 9 to rotate, these latter 75 wheels being mounted to rotate in unison on a shaft 24. It should be understood that the wheels 12 and 13 are rotatable in unison on a shaft 25 and that the wheels 14 and 15 are rotatable in unison on a shaft 26. 80

The wheel 9 meshes with a wheel or spur gear 27 which is mounted on a shaft 28 and rotatable in unison with this shaft and with a drum 29 which is studded with pins or studs 30 which engaged with a comb-like 85 member 31 which is formed with vibratory tongues which produce musical sounds when they are released from the respective pins of the drum 29. The arrangement of such vibratory tongues with relation to the pin-drum is publicly known, and is not here described in detail.

For the purpose of stopping the operation of the driving mechanism or motor, I may provide a suitable abutment 33 which 95 is movable into and out of the path of the fan 19 by any appropriate manipulative means, such, for instance, as indicated at 35. When the abutment 33 is moved out of the path of the fan 19 while the spring 31 is 100 under tension, the latter will drive the train of gearing, thus driving the drum 29 and causing the musical sounds to be produced.

It will be seen that the plate 8 closes the opening 6 of the doll's body or trunk, 105 and that this plate is provided with comparatively small openings through which the musical sound passes to the outer air. Because of the musical sounds being muffled within the hollow of the doll's body, the 110 metallic sound effects are modified so that the musical sounds simulate the human voice

while singing or humming. By increasing the size of any opening through the closing plate of the frame 7, the musical sounds will pass to the open air only slightly modified. A closure 36 may be provided for increasing and decreasing the size of the opening in the closing plate of the frame 7, so that the musical sounds may simulate the human voice or a musical instrument, at the will of the child or owner of the doll. Any appropriate means may be provided for securing the frame 7 to the body of the doll or figure toy, one means being indicated at 37, this element 37 being preferably a strip 10 of comparatively flexible metal having its intermediate part united with the closing plate, while its end portions extend to opposite sides of the doll's body and are provided with screw holes, so that screws may 15 be passed therethrough into the body of the doll or figure toy.

It is not intended to limit this invention to the combination of a doll's body with a musical instrument of this specific kind or 20 character, nor to the kind of motor here illustrated and described, nor is it intended to limit the invention to the placing of a musical instrument and driving mechanism within the body of a doll, it being within 25 the scope of this invention to apply a musical device and its driving motor within the body of a figure toy other than a doll. Therefore, changes may be made within the 30 scope of the inventive idea as implied and 35 claimed.

What I claim as my invention is:

1. The musical instrument which includes a frame having a plate as one of its elements, resonant elements of different musical tones, 40 a rotary member provided with means to impart vibrations to the respective resonant elements, driving means to rotate said rotary member, governing means to control the driving means; said frame combining with 45 said resonant elements, rotary member, driving means and governing means so as to form a unitary structure in which the last three named parts are arranged in substantially vertically extending row and form a mechanism that is relatively high and narrow 50 for being passed through a relatively high and narrow opening in a doll's body; said plate being relatively high and narrow and of a size to close said opening; means being provided to secure said plate in position to close said opening and support the said mechanism in the doll's body.

2. The musical instrument which includes a frame having a plate as one of its ele-

ments, resonant elements of different musical tones, a rotary member provided with means to impart vibrations to the respective resonant elements, driving means to rotate said rotary member, governing means to control the driving means; said frame combining with 60 said resonant elements, rotary member, driving means and governing means so as to form a unitary structure in which the resonant elements and the last three named parts form a mechanism that is capable of 65 being passed through an opening in a doll's body; said plate being of a size and shape to close said opening; means being provided to secure said plate in position to close said opening and support said mechanism in 70 said doll's body; said plate having an opening therethrough; and a closure movably secured on said plate and being operable to increase and decrease the size of the opening 75 of the plate, for the purpose specified. 80

3. The combination of a doll's body having a relatively high and narrow opening therein; a frame including a plate as one of its elements; resonant elements of different musical tones; a rotary member provided 85 with means to impart vibrations to the respective resonant elements; driving means to rotate said rotary member, governing means to control the driving means; said frame combining with said resonant elements, rotary member, driving means and governing means so as to form a unitary structure in which the last three named parts are arranged substantially in a vertical row and thus form a mechanism that is relatively 90 high and narrow for being passed through said relatively high and narrow opening of the doll's body; said plate being relatively high and narrow and of a size to close said opening while supporting said mechanism 95 in the doll's body; and means for securing said plate to said body in position to close said opening.

4. The combination of a doll's body having an opening therein, music-producing means capable of being passed through said opening, a plate supporting said music-producing means in the doll's body and substantially closing said opening when in the normal position, and a fastening strip having its intermediate part united with said plate and having its end portions normally extending substantially to opposite sides of the doll's body and provided with means securing these ends to the said opposite sides. 110

In testimony whereof I hereunto affix my signature.

MAXIMILLIAN A. MILLER.
